[57] CLAIM

The ornamental design of a fist on motorcycle engine clutch cover, as shown and described.

DESCRIPTION

FIG. 1 is a front elevational view of a fist on a motor cycle engine clutch cover showing my new design;

FIG. 2 is a bottom plan view thereof;

FIG. 3 is a right side elevational view thereof;

FIG. 4 is a left side elevational view thereof; and,

FIG. 5 is a top plan view thereof.

The broken lines shown in all drawing views are for illustrative purposes only and form no part of the claimed design.
